UNITED STATES PATENT OFFICE.

JOHN GOOD, OF NEW YORK, N. Y.

COMBING-MACHINE.

1,078,618.

Specification of Letters Patent. Patented Nov. 18, 1913.

Application filed February 27, 1911, Serial No. 611,114. Renewed May 14, 1913. Serial No. 767,719.

To all whom it may concern:

Be it known that I, JOHN GOOD, a citizen of the United States of America, residing in the borough of Brooklyn, city and State of New York, have invented the new and useful Improvements in Combing-Machines hereinafter set forth.

These improvements relate to high draft combing machines, particularly of the multiple feed type, and produce a novel form 10 of combing machine possessing extended capabilities in respect of the varieties of fibers that can be treated, as well as numerous other advantages which will hereinafter appear.

More especially the invention consists in a circular arrangement of the combing pin train and its several feeding devices, as illustrated for example in the drawings forming part hereof and in the various details of 15 such arrangement whereby various economies of labor and machinery are made possible, but many of the individual features of the invention which go to make up the circular multiple feed machine shown in the 20 drawing, are not limited to such type of machine, and can be used with advantage in other kinds of fiber-working machinery as will be evident to those skilled in this art. 25 These features form the subject of independent claims appended hereto, and include the means for doffing the fiber from the pins of the combing train whereby the sliver may be removed without exerting draft upon it, which possibility renders the machine useful 30 for combing certain very tenuous or short fibers that do not readily hold together in the form in which they would otherwise leave the combing pins. The said features also include the means for varying the comb- 35 ing rake without disassembling the machine, or while it is in motion, a matter of great importance in high draft combing apparatus and various other novel and useful devices and combinations; all of which will be more 40 readily understood when considered in connection with the drawings.

The drawings comprise six sheets, Figure 1 being a top plan; Fig. 2 a similar view with the feed heads, delivery head and plat- 50 form removed; Fig. 3 a vertical central section taken substantially on the line III—III in Fig. 1; Fig. 4 an enlarged end view of one of the feed heads with adjacent parts of the combing pin train; carriage and gearing 55 in section; Fig. 5 a radial vertical section

on line V—V of Fig. 2 on an enlarged scale; Fig. 6 a detail partly in horizontal section and partly in plan, of the combing pin train and its trackways and supports; and Fig. 7 a developed diagram of the combing pin 60 train with one of the feed-heads and the delivery head in elevation and parts of the combing pin train broken out and shown in section to indicate the operative relation of 65 the parts.

The frame of the machine comprises a series of radial girders 1, supported by legs 2 at their outer extremities, and at their inner extremities upon a central post or column 3 which forms the center of the machine, about which the carriage of the combing pin train revolves. The carriage comprises a sleeve 4 journaled to rotate on the central frame post 3 and vertically supported on the annular footstep 5 which supports the post and rests on the bed-plate or foundation. The sleeve forms the support for a series of radial arms 6 secured to the flange 7 thereon at equal angular intervals and supported at their outer ends by a corresponding series of tie rods 8 radiating from the head of the sleeve. The radial arms happen to be directly beneath the radial girders 1 of the stationary frame, as shown in Fig. 2, but the tie-rods 8 appear therein between the side plates of which those girders are formed. A circular rack 9 is attached to the underside of the carriage arms, and is normally in mesh with a drive-pinion 10 which is bevel-gearred to the power-shaft 11, through which the carriage is rotated, as clearly indicated in Fig. 5. The rack is shown as formed in segmental sections because of its very considerable diameter, but it will be understood that any proper means for rotating the carriage will serve the purpose as well as that indicated in the drawings. The outer ends of the radial carriage arms 6 form the support for two circular upright walls 12 and 13 which are secured thereon concentrically with the axis of the central post 3, providing an annular channel or space between them suitable for confining a combing pin train of desired width. In the present case, the combing train is formed of a series of gill bars 14 each bearing a row of combing pins and mounted on the carriage or in its walls 12 and 13 so as to be capable of rising 100 and falling movement therein. The sim- 105 110

plest, but not the only way of providing for such movement of the gill bars consists in mounting them in slots 15, in the two ring-shaped walls 12 and 13, so that the 5 vertical planes in which they are movable will be radial to the axis of the carriage, and spaced from each other by equal arcuate distances. As thus mounted, the end portions of each gill bar project through 10 their respective slots 15 into engagement with grooved trackways on either side which are fixed to the machine frame close to the carriage walls. As the carriage rotates, carrying with it the series of gill bars, the 15 latter are caused to rise or fall in accordance with the change in height of the trackways in different parts of the path of motion. The inner trackway is marked 16, being a continuous member provided with a 20 groove to receive the ends of the gill bars, and is supported upon several frame brackets 17 depending from the frame girders 1. The outer trackway is marked 18 and is formed of two parts or members adjustably 25 bolted to legs of the frame and providing between them an open slot through which the other ends of the gill bars 14 project. It will of course be understood that the groove of the inner trackway 17 and the 30 slot of the outer trackway 18 are parallel with each other, so that each of the gill bars will be maintained horizontal throughout its full travel around the machine. The end of each gill bar which projects into or 35 through the slot in the trackway 18, is provided with a dog 19, in the form of a single crank arm (Fig. 6) extending obliquely from the axes of the gill bar and terminating in a cylindrical boss 19^a, parallel 40 with the bar. As all the dogs are fast to their gill bars, the position of the bosses 19^a thereof with respect to the gill-bar trackway will obviously determine the angle of rake of the combing pins with which 45 each bar is equipped. These bosses are guided by their engagement in the independent trackway 20, which is parallel with the gill bar trackway for such portions of the circuit of the combing train as require 50 a constant angle of rake and departs from parallelism, upwardly or downwardly, according as the rake is required to vary. While the dog trackway 20 may be fixedly secured to the machine frame, it is preferably 55 mounted with provisions for vertical movement relatively to the gill bar trackways, and such means may consist of a series of three or more worm wheels 21, journaled on the frame legs and engaging worm 60 racks cut or formed in the outer side of the ring which forms the dog trackway. The worm-wheels are bevel-gearred to hand-wheels 22, by the operation of which the dog trackway 20 may be raised or lowered as 65 desired to change the angle of rake, and this

may be accomplished even while the combing pin train is in motion. The trackway moreover may be flexible or articulated if desired so that different degrees of change can be caused to be effected by it in different parts of the combing train's circuit by correspondingly manipulating the hand wheels 22 adjacent such parts. This means of variably controlling the rake is quite independent, as will be observed, of the structure or form of the combing pin train. It is applicable in obvious manner to combing pin chains of any of the usual types. Instead of shifting the dog trackway, however, the gill bar trackway could be shifted by the hand wheels with like effect, since it is the change in the relative position of one with respect to the other that controls the angle of rake.

The two ring shaped walls of the combing train carriage are spanned by a table or grid, formed in the present instance of a series of round rods 23 held in sockets in the upper margins of the walls and properly spaced so that the pins on the gill bars may project through the spaces between them. The height of the table above the pins is suited to the range of vertical movement of the latter so that when the pins move to their lowest positions their points will withdraw sufficiently below the upper surface of the grid rods or table to remove or doff any fiber that may have been previously engaged therewith and leave it resting freely on the tops of the bars. It will be obvious that any kind of table having openings through which the combing pins may project will be capable of performing a like function, relative movement between the table and pins being all that is necessary to effect the doffing of the fiber, and this being irrespective of which be the vertically movable part. The arrangement of the combing pin train of the kind above described, in the form of a horizontal flat annulus, possesses numerous advantages over ordinary combing pin instruments and constitutes a broad feature of the present invention. It will be observed for instance that substantially the whole length of the annular train is available for service, there being no idle stretch, as in the case of the ordinary hackle chain, and that the individual gill-bars are not required to move over short curves or corners or to engage with sprocket wheel teeth, and that they are at all times maintained in vertical planes which are equally spaced apart, whether the pins be in course of rising or falling, and finally that the arrangement makes for high speed with relatively little power.

Fiber is fed to the combing pin train from several points above the same by means of a series of circularly and tandem arranged feed-heads. All of these feed-heads may

130

be exactly alike and are so shown in the drawing, so that a description of one will suffice for all. As shown in Figs. 3 and 4, the several parts of the feed-head are carried in a frame work 24 of obvious construction which is secured to the radial frame girders 1 above referred to. A series of closely juxtaposed feeding cylinders 25, three in number in the present case, is mounted in the framework 24, each cylinder being journaled by its shaft 25^a to rotate on a horizontal axis, and driven by means of a shaft 26 having worm and worm driving connections 27 with each of them. The cylinder driving shaft 26 is bevel-gearred to an upright shaft 28 journaled on the frame lugs 2 and driven at the bottom through the spur gears 29 and 30 from the carriage rack 9 above referred to. There is one such shaft and set 15 of spur gears, driven from the carriage rack, for each feed head. The construction of the individual feeding cylinders 25, which are all alike, comprises a cylindrical, perforated drum or shell containing a series of gill bars which revolve in radial slideways therewith, with their ends projecting from the drum and guided in cam-plates at the opposite ends, so as to cause the pins thereon to project and withdraw through the 20 perforations as the cylinder rotates. The construction of cylinders of this kind is well known in the art and will not require further description. As arranged in the present case the cam plates, appearing at 31, are arranged to cause the projection of the pins on the lower sides of the three cylinders so as to form an inverted train of pins moving downwardly and toward the 25 combing pin train. Above the feeding cylinders there is an inclined feed-table 32 upon which bunches of fiber are adapted to be lapped together in the usual way to form a continuous lap of the fiber to be combed, which is then passed through an elbow chute 30 or conductor 33 at the lower end of the table, into engagement with the train of feeding pins formed by the three cylinders, which thereupon take it up and advance it toward the combing train. A board or 35 apron 34, supported directly opposite the inverted pins of the feeding train, and provided with hummocks 34^a to make it conform to the contour of the juxtaposed cylinders, serves to hold the fiber lap thereon during its movement. The organization of the combing train elements is such that the 40 combing of the laps fed in this way may be accomplished, either by immediate and deep penetration of the pins into the fiber, or by the so-called floating method, according to which the fiber is allowed to trail or ride on the top of the pins, floating on the pin-points as it were, so as to become gradually teased open and loose, allowing individual fibers to be pulled out of the un-

combed lap one after the other, and pass off onto the train, moving thereon to the delivery head. The difference in the action is determined by the position of the feed-heads with respect to the train of pins and also the rake of the latter as they pass the feed heads. In the one case the feed-heads are lowered close to the fiber table or grid 23, and the gill-bar trackways are made to give a dip to the train in order to clear the lower end of the feed head where it passes beneath it; in the other case, the feed head is higher and the pins move by without dipping. It will be obvious that the same machine may be quickly changed over to work according 50 to either principle. In the machine as shown, the fibers are subject to direct penetration by the combing pins, rather more than to the floating action, and for this reason, as shown in the developed view of Fig. 7, the gill-bar trackways 16 and 18 move downwardly as they approach the end of the feed-board 34 and then immediately rise into the fiber. The same action takes place at each feed-head, and after passing the last feed-head, the pins continue in elevated and parallel relation until they reach the delivery device. As the same combing operation is duplicated at each of the several feed heads, all of which 55 are intended to operate simultaneously, the fibers that are drawn off and taken up from each by the combing train, form a sliver thereon which is the composite of the several feeds, and therefore possesses an evenness 60 of weight represented by the average of the several separately supplied feeds.

The number of feed-heads and the draft of the combing pin train are obviously the chief controlling factors of the weight of the composite sliver that is formed on the combing train, and these may be varied in accordance with the work to be done, as well as with the nature of the fiber, as will be readily understood.

The delivery device shown in the case taken for illustration, comprises a pair of leather aprons 35 guided over rollers in a frame 36 at one end, and a further frame 37 at the other, the aprons being driven 65 in the direction of the arrows, by pulleys and belt 38, 39, through a change speed box 40, receiving its power from the drive shaft 11. The lower rollers of each apron are arranged with their axes substantially 70 radial to the combing pin carriage and in a position where the sliver introduced into the nip between them, will be taken up between the two contacting aprons 35 and thus removed from the combing train, but other kinds of fiber delivery means may be used, and delivery aprons like those shown may be obviously used in different ways, to perform the function of discharging the combed fiber from the pins or from the fiber table.

When it is desired to reduce the weight of the sliver that is removed from the combing train, the speed of the delivery aprons is set to exceed that of the train, so as to draw the fibers from the latter with a corresponding attenuation, and in such case it is desirable to cause the combing pins to reverse their forward angle of rake as they approach the delivery head, as indicated in Fig. 7, this being accomplished in the obvious manner by a corresponding change in the relation between the gill bar trackways and the dog trackways, as will be readily understood. The trackway which controls the elevation of the combing pins, is depressed as it approaches the delivery head so as to cause the train to dip under and clear the lower apron roller, thereby allowing the delivery head to exert a straight drawing pull on the fiber in substantially the plane of the pins, which arrangement is of obvious advantage. It is frequently necessary, however, with certain fibers to remove the sliver from the combing train with no draft whatever, and in such cases the pins are adjusted to recede through the grid somewhat earlier and leave the fiber lying freely on the grid fiber table as it approaches the delivery device, which may remove it therefrom in any suitable manner. If such delivery device comprises aprons like those referred to, they are of course properly adjusted as to speed to move at substantially the velocity of the combing train. The sliver moving upwardly between the aprons, whether removed with draft or without, is deposited at the top of the aprons upon a short conductor 41 over which it moves to the calender rolls 42 and thence to the sliver can shown at 43. The calender rolls 42 are driven by a belt 44 as will be plain from the drawings without further explanation.

A central platform 45 is placed on the frame structure within the circular combing train, on which the attendant stands to supply the fiber to the several feed heads, access to the platform for the attendant, as well as for the material handled, being provided by a section of flooring 46 crossing the combing train between the first feed head and the delivery head.

From the description above given the operation of the machine will be evident. It will be understood moreover, that the feed boards can be readily modified to take continuous fiber laps produced elsewhere instead of bunches of raw fiber, and that the combing draft can be varied as desired by interposing suitable gear combinations for the change gears 29 and 30 which drive the feed head shafts, so that the appropriate draft for every kind of fiber will be provided for. It will be further observed that the dipping of the combing train may be modified in various ways and as above ex-

plained, with or without simultaneous alteration in the angle of rake, and that the rake of the pins alone can be controlled by shifting the relation of the dog and gill-bar trackways in other ways than above indicated. The gill-bar trackways are preferably fixed parts of the machine frame and are not readily susceptible of bodily change of position nor of local flexing, for which reason modification of dipping motion of the combing pins is preferably accomplished by removing sections of the trackway where the change is desired and substituting other sections of the proper shape to give the elevation required for the pins. Both gill-bar trackways 16 and 18 and the dog trackway 20 are made and assembled in sections for this purpose and as indicated in Fig. 7.

While it is preferred to employ inverted trains of feeding pins, such as provided by the three adjacent feed cylinders 25 having self-housing pins, ordinary hackle chains could be used for this purpose with nearly the same facility, and moreover while it is preferred to mount the several feed heads on the frame which is stationary, it will be observed that it is possible for the combing pin carriage to be held stationary and for all the other parts to revolve.

I claim:

1. In a combing machine, a moving grid, a plurality of combing pins moving therewith, and means for imparting to said pins simultaneously with such movement two other movements, viz. a substantially end-wise movement relatively through the grid and an angular movement.
2. In a combing machine, an endless train of upright combing pins, an endless moving grid through which such pins may project to engage the fiber, and means for producing relative movement between the grid and pins to doff the fiber from the latter.
3. A combing machine comprising a flat and substantially horizontal grid forming a fiber table and means for moving the same, a train of upright combing pins projecting through the grid into the fiber thereon, and means for moving the pins relatively to the table to doff the fiber therefrom.
4. A combing machine comprising an extended flat fiber table and means for driving it, a train of pins projecting through the table, and means for feeding fiber to the projecting pins, in combination with means for producing relative movement between the pins and the table to free the pins from the fiber thereon and means for discharging such freed fiber from the table.

5. In a combing machine, a fiber table, a moving train of gill bars having combing pins projecting through the table, and means for feeding fiber to the projecting pins, said gill-bars having dogs in the form of crank arms and provided with a guideway co-

70

95

100

105

110

115

120

125

130

operating with said dogs to maintain the rake of the pins during the movement of the train.

6. In a combing machine a moving train of combing pins, means capable of adjustment while the train is moving to vary the rake of the pins and means for feeding fiber to the pins.

7. In a combing machine, a moving grid, a moving train of combing pins projecting through the grid, and means capable of adjustment while the train is in motion to vary the rake of the pins, in combination with means for feeding fiber to the train from a point above the same and a delivery head for the fiber.

8. In a combing machine a moving grid, a combing train having pins projecting through the grid and means for feeding fiber to said projecting pins, the pins for the portion of the train which is immediately adjacent to the fiber feed being parallel and forwardly inclined for operation on the fiber, in combination with means for withdrawing the pins from the grid to doff the fiber therefrom.

9. A combing machine comprising a fiber table, a moving train of pins projecting through the table, means for maintaining such pins in upright position, a train of feeding pins whereby fiber is fed to the pins projecting through the table, means for relatively moving the table and pins to doff the fiber from the latter, and means for delivering the combed fiber.

10. In a combing machine, a fiber table, a combing pin train projecting through the table into the fiber thereon, and having means for maintaining the pins thereof in substantial parallelism throughout the portion thereof which engages and combs the fiber, in combination with means for feeding the fiber to the said pins from a point above the same and a sliver delivery device.

11. In a combing machine a train of gill-bars having a trackway on which the train moves, dogs on the gill-bars and a trackway for the dogs and means for changing the relative positions of said trackways to vary the rake of the pins of the gill-bars.

12. In a combing machine, a train of gill-bars movable in a trackway and having dogs also movable in a trackway, one of said trackways being fixed and the other movable and a machine element for moving the movable trackway to vary the rake of the gill-bar pins.

13. In a combing machine, a train of gill-bars having a trackway in which the train moves, adapted to produce rising and falling movement of the gill bars, dogs on the gill-bars, a trackway for the dogs and means for varying the relation of the two trackways to vary the rake of the gill-bar pins.

14. In a combing machine, a moving grid

forming a table to support the fiber, a train of combing pins moving with the table and projecting through the same, in combination with means for feeding fiber at successive points along the length of the train of pins, means for relatively withdrawing the pins from the fiber on the table and a sliver delivery head.

15. In a combing machine, a moving grid, a combing pin train projecting through the grid and moving therewith, plural means for feeding fiber to the projecting pins, means for relatively withdrawing or separating the train and grid to doff the fiber from the pins and a single sliver delivery head.

16. In a combing machine, a moving train of gill bars maintained respectively in vertical planes that are separated by a non-varying distance throughout the entire path of motion of the train.

17. A circular combing machine having a space in the center for the attendant.

18. A circular combing machine comprising an endless train of combing pins and having a platform in the center for the attendant, and an entrance to such platform overlying the said train.

19. A combing machine comprising a number of feed-heads arranged in positions substantially equidistant from a central point, and adapted for independently advancing the fiber into the combing pin train, in combination with a combing pin train and delivery head common to all the feed heads.

20. A combing machine having a circular train of combing pins, a plurality of means for continuously feeding fiber thereto arranged above the train to feed the fiber downwardly thereto, and a delivery head common to several feeding means.

21. In a circular combing machine, a carriage comprising two concentric annular walls, upper and lower sets of cross-members spanning said walls, one of said sets being carried in trackways adjacent the carriage and adapted to have rising and falling movement with respect to the other, and pins on the members of one of the sets.

22. In a circular combing machine, a rotary carriage formed of concentric annular walls, a set of cross-members fixed thereon and forming an annular fiber table, and a set of gill-bars mounted for vertical movement in the carriage, in combination with a cam track adjacent the carriage to produce such movement of the gill bars therein.

23. In a circular combing machine, a rotary carriage provided with an annular fiber table, and carrying a train of gill bars with provisions for vertically moving the same to project the pins thereof through the table, in combination with means for feeding fiber to the projecting pins.

24. In a combing machine, a carriage hav-

6
ing gill bars provided with dogs and mounted in vertical slots in the carriage, a generally horizontal trackway supporting the bars in the carriage, and a substantially parallel trackway for the gill bar dogs.

25. In a combing machine, a train of gill bars, a moving carriage therefor, dogs on the gill bars having obliquely disposed and successively overlapping crank arms, a trackway for the gill bars and a second trackway for the dogs thereof.

26. In a circular combing machine, a rotary carriage, an annular combing pin train moved thereby, and several feed-heads for said train, each receiving its driving motion from the said rotary carriage.

27. In a combing machine, an annular train of upright combing pins having different rake in different portions of its path of movement.

28. In a combing machine, a plurality of fiber feeding means arranged one behind the other, and all contributing their feeds to a single combing pin train, in combination with such train and means for causing the pins thereof to have direct penetration into the fiber fed by said feeding means.

29. In a combing machine, a plurality of

feed-heads tandem arranged and feeding to a single combing pin train, in combination with such train having means for causing its pins to directly penetrate the feed from each feed head, and a single delivery mechanism producing a composite sliver from the several feeds.

30. In a combing machine, a moving combing-pin train and means for feeding fiber to be combed thereto, in combination with means for causing a dip in the path of the pins at a point in advance of the point of feed.

31. In a combing machine, the combination of a substantially flat, moving, combing-grid provided with combing pins adapted to fall and rise through the same, a feed-head above the grid adapted to project fiber into the path of said pins and means for depressing said pins as they pass the feed head.

In testimony whereof, I have signed this specification in the presence of two witnesses.

JOHN GOOD.
